UNITED STATES PATENT OFFICE.

ALBERT O. JOHNSON, OF NORTHWOOD, IOWA.

ADJUSTABLE SHOW-CASE.

1,345,367.

Specification of Letters Patent.

Patented July 6, 1920.

Application filed September 22, 1919. Serial No. 325,350.

To all whom it may concern:

Be it known that I, ALBERT O. JOHNSON, a citizen of the United States, and resident of Northwood, Iowa, have invented certain new and useful Improvements in Adjustable Show-Cases, of which the following is a specification.

One object of my invention is to provide a show case in which the articles to be stored or displayed will be held in separate supplemental cases or compartments each of which is adjustable to and from the point of display or the point of accessibility so that while the goods in one of the supplemental cases or holders are accessible at the display point, an extra stock of the material will be held in the other case or compartment in storage and this latter compartment may be moved to the point of accessibility or display after the first compartment has become empty and has been moved away from the point of display or accessibility. By the use of this invention wall space or other space is utilized in a store that is normally out of reach from the floor for displaying and selling goods.

The invention is shown in the accompanying drawings in which:

Figure 1 is a vertical sectional view of a show case embodying my invention.

Fig. 2 is a plan view.

Fig. 3 is a front view.

Fig. 4 is a sectional plan view substantially on the line 4—4 of Fig. 1.

Fig. 5 is a sectional view substantially on the line 5—5 of Fig. 4, and

Figs. 6 and 7 are vertical sectional views similar to Fig. 1 but showing the parts in the different positions they assume during the course of use of the show case.

Referring to Fig. 1 the reference character 2 indicates a section or main casing composed of a top 2', a bottom 2'', suitable sides as shown in the sectional plan view, and a front panel 2* having a pane of glass therein, this panel extending from the top of the main casing or section down to a point about midway of the height of the main casing. Within this casing there are two supplemental cases or holders indicated at A and B. Each of these is of boxlike form and each may have any suitable number of shelves such as indicated at 3. These cases A and B are open at their front sides as shown at C Fig. 4 so that access may be had to the interior of these cases for placing

or removing the goods and for obtaining a view of the goods held in these compartments or cases.

The lower case A has rollers 4 mounted upon suitable ways or tracks 5 in the bottom of the main housing so that when this case A becomes exhausted of its goods it may be pushed to the rear to the position indicated at A' Fig. 1 in dotted lines, or as shown in Fig. 6 and then the other case or compartment B can be lowered from its elevated position shown in Figs. 1 and 6 so as to occupy the position previously occupied by the lower case A, so that the two cases will then occupy the position shown in Fig. 7 and access may be had to the casing B to withdraw goods therefrom or for refilling this casing.

The casing B is suspended by flexible connections 6 passing over pulleys 7 supported by the top of the main housing or section, these flexible connections or cords extending rearwardly over the pulleys 7' and thence down to a cross piece 8 carried by rods or shafts 9 extending parallel with the side walls of the main housing and close to the same, the forward portions of these rods or shafts being supported by the bearings 10 which are journaled in the side walls of the main housing at 11. These rods 9 carry counter weights 12 and the rods are screw threaded so that by turning the hand wheels 13 the rods or shafts will be turned to adjust the counter weight along the rod so that the varying weight of the casing B with its supply of articles or goods will be compensated for by the adjustment of the weight 12. The two rods or shafts 9 are interconnected so that in making the adjustment it is necessary only to rotate one of the hand wheels 13, that is, which ever one is most convenient, but of course both may be turned if desired. This interconnection between the two shafts is affected by bevel gearing 14 and a cross shaft 15 bearing in the cross member 8. This cross member 8 has at its ends suitable bracket extensions 16 which afford the bearings for the rear ends of the shafts or screw rods 9. As before indicated, when the supply of articles or goods in the compartments of the lower casing A become exhausted this is pushed to the rear and then the other casing B is lowered to bring its interior to the point of accessibility.

This casing B therefore is intended to

contain an extra supply of the goods, but when the casing B is still filled or partly filled and is in the position shown in Fig. 1 where its supply is accessible, the casing B 5 will act as a storage chamber and will occupy a space above the chamber or casing A where it will be out of reach. In order to close the front of the main housing or casing a movable panel is provided at D 10 adapted to close the opening between the lower edge of the fixed panel 2* and the bottom of the housing and this movable panel D may have a pane of glass therein as indicated. This movable panel is counter balanced by a weight 17 connected by a cord 18 running over pulley 19 and thence down to the panel D at the point 20.

The apparatus may be used in clothing stores or in other situations and may be used 20 for displaying clothing or any other class of goods. A number of the sections or housings 2 may be arranged side by side and each housing will contain the two supplemental cases or compartments A and B. By 25 the use of the apparatus an extra supply of the goods may be kept in storage but ready for immediate use when the store of goods in the case A has become exhausted.

I claim as my invention:

30 1. In combination a main housing, a pair of cases therein for containing goods, one arranged above the other at the front of the housing, the lower case being movable toward the rear and the upper case being vertically movable, flexible connections for suspending the upper case, a shaft pivotally mounted near its front end and screw threaded and having a weight thereon, said screw shaft being connected with the flexible 35 connection.

40 2. In combination a main housing, two goods-containing cases therein, one movable to the front or rear and the other movable vertically, flexible connections suspending the vertical movable case, a pair of screw shafts pivotally mounted near their ends, weights adjustable on the screw shafts, means for interconnecting the shafts, said shafts being connected with the flexible 45 suspending means.

50 3. A display apparatus comprising a main

housing, a pair of display cases therein, one having vertical movement upwardly and downwardly but restrained against horizontal movement and the other case having only 55 horizontal movement, both of said cases being movable to and from the same point of display within the housing.

4. A display apparatus comprising a main housing, a pair of display cases therein, 60 one having vertical movement upwardly and downwardly but restrained against horizontal movement and the other case having only horizontal movement, both of said cases being movable to and from the same 65 point of display within the housing, means for counterbalancing the vertically movable case and means for adjusting said counterbalancing means extending to the front of the housing. 70

5. A display apparatus comprising a main housing, a pair of display cases therein, one of said cases being suspended to move vertically up and down and the other case having only horizontal movement to and 75 from the point of display, counterbalancing means for the vertically movable case comprising ropes extending from the said case up through the housing and to the rear thereof and then downwardly, and means 80 for subjecting said ropes to downward stress at their rear portions, and means for adjusting the said stress.

6. In combination in a display apparatus, a housing, a display case therein, movable 85 vertically up and down at the front of said housing, and a second case movable horizontally toward the front and back of the said housing, and means for guiding the cases, the one to move only vertically and 90 the other to move only horizontally to and from the same display point.

7. An apparatus of the class described comprising two sets of shelving within a casing, one movable to a point of display 95 vertically, the other movable to the same point of display horizontally, the movement of one set being prevented without first moving the other from the common point of display. 100

In testimony whereof, I affix my signature.

ALBERT O. JOHNSON.
